WOLFGANG E. SCHWARZMAN, OF LONGMEADOW, MASSACHUSETTS, ASSIGNOR TO AMERICAN BOSCH MAGNETO CORPORATION, OF SPRINGFIELD, MASSACHUSETTS, A CORPORATION OF NEW YORK

MAGNETO INTERRUPTER

Application filed February 25, 1930. Serial No. 431,106.

My invention relates to improvements in circuit breakers or interrupters, particularly interrupters of the type used on magnetos for igniting the combustible motive agent in the power chambers of internal combustion engines.

An object of the invention is to provide an interrupter for a magneto of simple and inexpensive construction and comprising relatively few parts which can be readily assembled or dismounted.

Another object of the invention is to provide an interrupter embracing a pair of contacts mounted so as to be relatively movable and adapted to engage and disengage each other, one of the contacts being suitably insulated and connected in the circuit of the magneto by special means which also acts to hold the contacts together.

A further object of the invention is to provide an interrupter comprising a breaker lever which is partly of insulation and partly of conductive material, with a spring to maintain the lever in circuit closing position, and at the same time connect the lever to the winding of the magneto controlled by the circuit breaker.

An additional object of the invention is to provide a circuit breaker or interrupter comprising a movable lever that is retained in position by a holding element, such as a spring, which is movable to enable the lever to be quickly taken off when necessary.

Other objects and advantages of the invention will be made clear in the following description and drawing, in which a preferred embodiment of the invention is illustrated. But this disclosure is explanatory only, and changes may be made in the interrupter herein set forth as regards matters of shape, size and arrangement of parts, without going beyond the principle of the invention or exceeding the scope and meaning of the terms in which the appended claims are expressed.

In the drawing, Fig. 1 is a side view of an interrupter according to my invention; Fig. 2 is a front view thereof with lever in circuit-closing position; Fig. 3 is a fragmentary front view showing the contacts separated;

Fig. 4 is a side view seen from the left of Fig. 2, for example showing the parts in position for assembling; Fig. 5 is a front view with some of the parts in section; Fig. 6 is a perspective view of a block of insulation forming part of the interrupter lever; and Fig. 7 is a perspective view of the conductive portion of the interrupter lever with the end of the operating spring attached.

The same numerals identify the same parts throughout.

The numeral 1 indicates a supporting member or disc, which is of metal and is provided with a central bearing 2 to enable the interrupter to be secured to the forward trunnion or journal of the armature of an ignition magneto of any well known design. The magneto may be of either the high tension or low tension type and connection may be made between the breaker and the ungrounded terminal of the low tension winding on the armature through a bore or passage in the shaft or journal on which the bearing 2 is fitted. As usual, this shaft or journal will be provided with a key to engage a keyway in the bearing 2, so that when the armature rotates, the circuit breaker will rotate with it. The disc 1 has a projection 3 extending at right angles to its outer face at one point of the edge thereof, and this projection will have a threaded hole to receive and carry a screw 4, one end of which bears an electrode 5 of suitable material. The numeral 6 indicates the movable electrode, which is mounted upon the breaker lever 85 comprising the parts 7 and 8, the former being a simple plate of metal and the latter a block of insulation to which the metal plate 7 is affixed. This breaker lever is mounted upon a pivot or journal 9 and moves on the journal as an axis to cause the electrodes 5 and 6 to come together or separate as the armature and circuit breaker revolve. The disc 1 with its central hub or bearing 2, projection 3 and journal 9 may be all made in one piece.

A binding nut 10 is carried by the screw 4 on one side of the projection 3. The head 11 bearing the electrode 5 on the opposite side of the projection may be used to turn the screw 100

4 to adjust the electrode 5, and the nut may be employed to secure the screw 4 in adjusted position.

The block of insulation 8 has a central bore 12 to receive the journal 9 and a groove 13 extending across one end. At 14 is an opening for a screw and the plate 7 has a cooperating opening 15. This plate may be bent transversely to provide a shoulder 16 near the middle; the end or portion on one side of this shoulder having the opening 15 being received in the groove 13. At 17 is a screw which passes through the holes 14 and 15 and is held fast by a nut 18, and the block 8 is provided with a recess 19 which receives the nut 18. Thus the plate 7 and block 8 are made rigid with each other and constitute a single unit. The block 8 may be provided at one corner with a projection or nose 20. As usual, the magneto of which this breaker is a part will be provided with cam projections in stationary position, and as the armature with the breaker rotates, the nose 20 will strike these cam projections, with the result that the breaker lever is moved to separate the electrodes 5 and 6. As shown in Figs. 1 and 4, the journal 9 is provided with a shoulder 21, against which the block 8 fits.

The screw 4 and electrode 5 are, of course, electrically connected to the disc 1 but the metal plate 7 and electrode 6 are insulated. To connect the electrode 6 in the circuit of the armature, I attach to the disc 1 a contact piece 22. Between this contact piece 22 and the disc 1 is interposed a sheet of insulation 23, and the piece 22 has a projection 24 extending away from the disc 1. To this projection is screwed one end of a curved spring 25. The opposite end of this spring is attached to the outer end of the plate 7 by means of a rivet 26. Washers 27 may be employed in connection with this rivet on both faces of the plate 7, and the electrode 6 is a part of this rivet. To attach the spring 25 to the projection 24, I may employ a rivet 28, or a screw, or any other suitable means. The contact piece 22 and the insulation 23 may have registering openings 29 in line with the bore of the hub 2 and when this hub is mounted on the end of the armature shaft, a stem or bolt having a head thereon may be thrust through the openings 29 until the head of said stem abuts the outer contact face of the piece 22. The inner end of the stem will engage a suitable metal part by which connection is made with the armature winding; and thus through this stem, which is not shown, a circuit is completed from one end of the armature winding to the piece 22, and through the spring 25 to the electrode 6, electrode 5 and the frame work of the magneto to the opposite or grounded terminal of the armature winding. Normally, this circuit is kept closed by the spring 25, but whenever the nose 20 strikes one of the cam projections

above mentioned, the circuit will be opened and sparking will take place.

To secure the contact piece 22 in place, I may utilize a screw or rivet 30 which passes through the contact piece 22 and the insulation 23, and is held fast to the disc 1. The hole in the piece 22 through which the rivet 30 passes will be larger than the thickness of this rivet, and between the head of this rivet and the contact piece 22 is an insulating washer 31. Hence this rivet does not make contact with the piece 22. The hole for the rivet 30 through the contact piece may be of the size indicated at 32 on Fig. 4, and the larger holes for the rivet through the insulation 23 and disc 1 are indicated at 33 on this figure. The holes shown in Fig. 4 are additional holes for the double purpose of further securing the contact piece 22 and attaching to the disc 1 a post 34 having a shank 35 of less thickness than the width of the hole 32. This shank passes through the holes 32 and 33, and its end is expanded or riveted, attaching it permanently to disc 1 the same as with the rivet 30. Between the post 34 and the end shoulder thereof from which the shank 35 projects, is an insulating washer 36 which is held by the post 34 tightly against the contact piece 22, so that there is no metallic connection between the post 34 and the contact piece 22. This post and the rivet 30 thus bind the contact piece 22 and disc 1 together.

To the outer end of the post 34, I attach a spring 37 to serve as a holding element for the block of insulation 8. A screw or rivet 38 anchors the spring 37 to the post 34 and permits the spring to be swung about this rivet as an axis. The opposite end of the spring 37 has a projection 39 and this end is bent slightly further away from the disc 1, so that, while it passes over the edge of the spring 25, it does not touch this spring. At 40 is a cap having a recess 41 in one face, and a projection 42 on the opposite face. This cap closes the outer end of the bore 12, and the projection 42 enters this bore, so that the cap covers the end of this bore and the end of the journal 9 therein. The spring 37 is so set that the projection 39 enters the recess 41 in the cap 40 and exerts enough pressure on this cap to keep it in place. Hence, the block 8 and the interrupter lever are forced against the shoulder 21 and kept in position when the magneto is in operation; and by pulling the end of the spring with the projection 39 away from the block 8, this holding spring can be swung to one side so that the cap 40 can be taken off, and then the entire interrupter lever can be removed from the journal 9.

The disc 1 may also be provided with an integral hollow socket 43 which opens through the same face on the disc as the hub 2, and in this socket is the usual spring-pressed ground brush 44 to rub upon the end plate of the

magneto while the breaker is rotating, and give an efficient connection through the frame work of the magneto to the grounded terminal of the armature winding.

5 The breaker is thus seen to be made up of parts which can be very easily shaped and fitted together and which can further be very readily dismounted when the breaker is in need of adjustment or repair, or whenever any 10 part needs to be replaced. The relatively fixed contact is the grounded contact 5, and the electrode 6, which is movable, is insulated from the body of the interrupter or disc 1, and therefore from the framework of the 15 magneto, but is nevertheless connected in circuit with the armature through the spring 25, which normally holds electrodes 5 and 6 together. This spring, directly attached to the projection 24 of the contact piece 22, is electrically united by the stem (not shown), that 20 engages the contact piece 22 and goes through the hub 2 into the armature shaft to make connection with the armature winding. The entire assemblage is thus very compact and 25 very efficient in practice.

Having described my invention, what I claim is:

1. A circuit interrupter comprising a supporting member of electrically conductive material having a perforated projection, a fixed contact held by said projection in circuit with said member, a contact piece secured to said member, insulation separating said piece and said member to keep said piece out of 35 electrical connection therewith, said piece having a projection and said member a journal, a block of insulation pivoted on said journal, a metal plate bearing a cooperating contact affixed to said block, and a spring attached to said plate and the projection on the contact piece and normally actuating the plate to keep said contacts in engagement with each other.

2. An interrupter comprising a supporting 45 member of electrically conductive material, a fixed contact on said member and in circuit therewith, the latter having a journal, a lever made up in part of an insulating block having a bore receiving said journal to mount 50 said lever, a contact carried by the lever, means insulated from said member for establishing connection with the last named contact and acting normally to hold said contacts in engagement with each other, a post 55 secured to said member and insulated from the contact on the lever, a spring pivotally secured to said post, and a cap for engaging the lever adjacent said journal and to be pressed upon by said spring for detachably 60 holding the lever in place on said journal.

In testimony whereof I affix my signature.
WOLFGANG E. SCHWARZMAN.
